SUPPORTING DEVICE

Ladimer M. Moenik, Cleveland, Ohio

Application August 16, 1944, Serial No. 549,723

8 Claims. (Cl. 248—303)

1

This invention relates to and an object is to provide a supporting device or clip on which sheet material such as paper may be readily mounted or suspended without requiring fasteners or other means likely to crease, perforate or otherwise damage the material.

Another object is to provide a supporting device such as outlined above having an improved means for mounting of the same as on a wall, table or other base.

A further object is to provide, in combination, a supporting device for paper or the like made from adjacent spiral turns of spring wire and a bracket cooperating with one or more of the turns or coils of wire for holding the device in mounted or operating position.

Still another object is to provide a coiled spring wire supporting device or clip for sheet material incorporating an improved means to facilitate spreading of two or more of the coils apart sufficient distances to receive readily the material to be supported and to enable release thereof without danger of damaging the material.

A still further object is to provide a clip or support of the character indicated above made in one piece from coiled spring wire and having means for receiving a fastener substantially centrally of the coils for holding the support in fixed mounted position as on a wall.

Other objects and features will become apparent from the following description of the illustrative forms of the device shown in the drawing, wherein:

Fig. 1 is a central longitudinal sectional view in a vertical plane of the device in one form and in enlarged scale;

Fig. 2 is a front elevation of a sheet metal attaching bracket for the wire portion of the device in the same form;

Fig. 3 is a central longitudinal sectional view of a somewhat modified form;

Fig. 4 is a transverse sectional view of a different form of the device made in one piece from coiled spring wire, and

Fig. 5 is a central longitudinal sectional view of substantially the same form as partially shown by Fig. 4, but with modified attaching-bracket-forming coils or turns of wire.

Adjacent helical turns of spring wire (coil spring form) have been heretofore proposed or used for temporarily supporting sheet material, pencils and other articles. The present invention comprises an adaptation of that known device and particularly comprises improved means for utilizing it as a clip or support adapted to be

2

firmly mounted on any surface capable of receiving and retaining a fastener such as a nail or screw.

Referring further to the drawing, Figs. 1 and 2 show the sheet supporting member 1 of the device in the form of a closely coiled wire spring. The coils, in the particular form shown, decrease in diameter toward one end of the coil assembly 2, indicating the free end of the coil member 5 when in attached or mounted position. The terminal coil 3 at the left, for attachment of this form of device, is mounted in a disc-like bracket member 4 preferably of sheet metal and designed to receive and retain substantially the entire terminal coil 3 behind the bracket to hold said coil and hence the entire coil spring portion of the device firmly in place on a wall or other support to which the bracket is attached as will be described below.

20 The bracket 4 as shown particularly in Figs. 1 and 2 has a central disc portion 5 apertured as at 6 to receive for example an attaching screw 7 by which the bracket may be firmly supported on a wall 9. The work-retaining turns of the coil spring portion of the device are indicated generally at 8. The screw or attaching device 7 can be most easily assembled with the bracket before the spring coil portion of the device is attached to the bracket. The recommended manner of 25 mounting the device as on a wall is first to screw or nail the bracket into place and then attach the coil spring member to the bracket. The bracket 4 has a laterally directed circular flange 10 at the margin of the central disc portion 5, the flange being continuous in the particular form illustrated from one side of a cut away portion 11 (Fig. 2) of the disc to the other side of said portion.

In order to assist the flange 10 in holding the 30 terminal coil 3, there are provided on the disc portion 5 a series of outstruck bosses or projections 12 shown as three in number distributed around the central opening 6. These may extend far enough out of the plane of the central portion 5 of the disc nearly to touch the face of the supporting wall 9 as shown on Fig. 1. Thus the central portion of the disc is prevented from being distorted out of its proper position by the force exerted by the head of the fastener and the coil 3 is guided and frictionally retained both on its inner and outer peripheral surfaces. Part of the terminal coil 3 is shown in Fig. 2 in initial assembly position with respect to the bracket, from which position the coil 3 may be inserted into 35 final position in engagement with the entire in-

inner surface of the flange 10 and into contact with all the projections 12 simply by initially positioning the spring coil part of the device as indicated above and then turning said part about its longitudinal axis. Preferably the fastener is not driven home against the disc until after assembly of the spring coil part therewith as described above and, after assembly, in case the fastener is a screw, a screw driver is passed through the coils and the screw further turned to cause the bracket to exert strong clamping force on the terminal coil 3. Preferably also the space provided for the terminal coil 3 between the disc and the face of the wall 9 is greater than the projected length of the flange 10 so that the edge 10a of the flange 10 does not engage the face of the supporting wall in such manner as to prevent the strong clamping force of the bracket against said terminal coil 3.

In the claims the flange 10 is said to be interrupted in order to receive the terminal coil. While only one such interruption is shown (provided by the cut-away portion 11) the flange may be additionally interrupted at other places.

To provide a suitable handle at the free end of the coil member 2, one or more outer terminal coil or coils, one being shown at 14, is or are bent outwardly as at a right angle to the adjacent undistorted coil. The outwardly bent handle-forming terminal portion of the wire need not necessarily be a loop such as constituted by the bent out terminal coil. The handle may be of any other suitable shape. Its purpose is to assist in spreading the coils apart as by lifting the handle, see Fig. 5, with an applied force such as indicated by the arrow A. When so spread the coils easily receive the material to be supported and the generally tapered form of the coil spring member is of advantage in that connection as will be obvious from Fig. 5. The work W, indicating for instance a piece of paper or a card, is moved into contact with one of the coils as in the direction of the arrow B, Fig. 5, until it abuts one of the coils which is spread apart from its adjacent coil; and then by movement of the work at right angles to the direction B, the work is inserted into final supported position as shown in Figs. 1 and 3, being strongly gripped between adjacent coils 8.

The construction shown by Fig. 3 differs from that of Figs. 1 and 2 mainly in the direction in which the flange 10a on Fig. 3 is turned with reference to the central disc portion 5a of the bracket. As shown the flange 10a is curled in order to receive the terminal coil 3 somewhat in the manner of a female thread although it is, of course, not necessary that such female thread effect have any inclination or pitch since in turning the terminal coil into the embrace of the curled flange, said coil will be sprung out of its normal inclined or pitched position. The flange 10a could be formed as a male thread effect for engagement with the inside surfaces of the wire coil or coils as desired and in any event either one or more coils may be frictionally engaged by the flange. The flange 10a could be interrupted exactly as shown in Fig. 2, that is, by a cut-away portion 11 of the bracket, or in any other suitable manner.

The under side of the central disc portion of the bracket may be concave so that if the head of the fastener flattens the disc portion against the surface of the supporting wall 9, the flange 10 is given a further tendency to grip the terminal coil firmly.

If the inner diameter of the curled flange is somewhat smaller than the outer diameter of the

terminal coil 3 there will be sufficient frictional force exerted by the wire against the inner surfaces of the flange to hold the coiled wire member firmly in position without the employment of additional wire engaging means such as afforded by the projections 12, although, of course, in the form shown in Fig. 3, said projections or a circular rib could be provided for such additional frictional engagement purposes.

10 As an alternative method of attaching the coiled spring member (see Figs. 4 and 5) one or more turns of wire (one shown in Fig. 4 at 15 and several shown in Fig. 5 at 15a and 15b) are brought inwardly toward the axis of the member 1 and form an eyelet or supporting loop or pad for receiving the shank of the attaching fastener 1a. If several closely adjacent or abutting turns of the wire are used to form the eyelet the relatively outer turns 15b may be employed to 20 brace or buttress the inner one 15a which receives the fastener shank.

In the case of forming the attaching base from the wire stock, as described in connection with Figs. 4 and 5, the handle loop is disposed sufficiently eccentric to the axis of the coils generally 25 so as not to prevent the head of the fastener from being easily passed through the outer or free terminal coil and so as not to obstruct the free passage of a screw driver or nail set through the coils. The coils 15a and 15b, Fig. 5, are preferably in mutual contact but they need not be.

With the present device the sheet material to be supported is held very firmly and in the case of cards and the like may be inserted at the upper 30 portions of adjacent coils or at the side for display or other purposes. Several of the devices can be used to support and display large signs, blue prints, pictures, etc., as at the upper and lower margins of the work. The device can, of course, be mounted in any position, for instance on a horizontal surface for preventing papers from being blown off such surface or too readily displaced from the desired position thereon.

In the claims the expression "closely wound" in reference to the coils of wire does not necessarily mean that the coils normally touch each other although that is the preferred arrangement.

I claim:

1. A device of the class described comprising a base in the form of a disc adapted to be secured to a generally flat surface and having a marginal flange, said flange being interrupted at one side of the disc, and a member in the nature of a helical spring having a terminal coil supported for more than half its circumferential extent by inner surface portions of the flange and adjacent marginal portions of the disc, said terminal coil being insertable into supported relationship to the base at the region of interruption 55 of the flange.

2. A support or clip of the class described, comprising a closely wound helical spring having means at one end for enabling attachment of the spring firmly against a supporting surface by 60 said end with the opposite end free, one of the coils at the said opposite free end of the spring projecting generally endwise of the spring with its axis disposed transversely of the spring axis to serve as a handle for spreading the coils apart to work-receiving position.

3. A support or clip comprising a helical spring member adapted to support sheets and the like between adjacent coils, and a disc-like supporting bracket at one end of the coil assembly and 70 adapted to be connected to a supporting struc-

ture and having a flange in peripheral frictional contact with the adjacent coaxial terminal coil of the spring member and detachable therefrom by rotation of the coil and bracket relatively in opposite directions about their common axis, and the other end of the coil spring member being free.

4. A support or clip according to claim 3 wherein in the disc has a portion extending out of the plane of the disc in the same direction as the flange for additionally peripherally supporting the said terminal coil against displacement laterally of the disc.

5. A support or clip comprising a closely coiled helical spring member adapted to support sheets and the like between adjacent coils, and a disc-like supporting bracket at one end of the coil assembly and adapted to be secured against a wall, said bracket having a flange positioned to face toward such wall when the bracket is supported in operating position on said wall, said flange being in supporting engagement with a terminal coil of the spring member.

6. A support or clip for demountably carrying sheet material such as paper comprising a closely wound helical spring having one end free, a supporting base connected to the spring at the other end of the spring and adapted to receive centrally of the spring a fastener, such as a nail or screw, for securing the spring in fixed relation to a supporting surface at said other end with the coils generally parallel to the supporting surface, and

said base lying substantially within the peripheral limits of said other end of the spring and being substantially concealed by the spring.

7. A spring clip comprising supporting means adapted to be connected to a supporting structure, a helical spring connected at one of its ends to the supporting means and supported thereby and having its other end free, said spring having all of its coaxial convolutions, between the supporting means and its free end, in end to end resilient contact with each other.

8. A spring clip comprising a support, a helical spring connected at one of its ends to the support and having its other end free, and means rendering said spring uncompressible axially when the spring is supported by said support.
